US0D1041002S

(12) **United States Design Patent** (10) **Patent No.:** **US D1,041,002 S**
(45) **Date of Patent:** **** Sep. 3, 2024**

(54) **MOUNTING PLATE**

(71) Applicant: **American Sterilizer Company**,
Mentor, OH (US)

(72) Inventors: **Lance Clark Bellows**, Painesville, OH
(US); **Michael Joseph Heser**,
Willoughby, OH (US)

(73) Assignee: **American Sterilizer Company**,
Mentor, OH (US)

(**) Term: **15 Years**

(21) Appl. No.: **29/829,698**

(22) Filed: **Mar. 7, 2022**

Related U.S. Application Data

(62) Division of application No. 29/725,038, filed on Feb.
21, 2020, now Pat. No. Des. 945,606.

(57) **CLAIM**

The ornamental design for a mounting plate, as shown and
described.

DESCRIPTION

FIG. 1 is a top perspective view of a mounting plate showing
our new design;

FIG. 2 is a top plan view thereof;

FIG. 3 is a bottom plan view thereof;

FIG. 4 is a bottom perspective view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines in the drawings illustrate portions of the
mounting plate and form no part of the claimed design. All
contour lines shown in each drawing are lines representing
surfaces of the solid body and form no part of the claimed
design.

1 Claim, 5 Drawing Sheets
